Attorney

UNITED STATES PATENT OFFICE.

CLARENCE E. STRICKLAND, OF ATLANTIC CITY, NEW JERSEY.

BLADE HOLDER.

Application filed April 5, 1927. Serial No. 181,080.

This invention relates to blade holders and has relation more particularly to a device of this kind especially designed and adapted for use in connection with those kinds of 5 razor blades of a flexible type and which are generally employed with safety razors, and it is an object of the invention to provide novel and improved means whereby such a blade may be conveniently and effectively 10 mounted to facilitate the use of such blade as a scraper for removing foreign matter from glass surfaces or the like and also to enable the blade to be employed with facility as a cutter, such as can be used in 15 ripping seams and the like.

The invention consists in the details of construction and in the combination and arrangement of the several parts of my improved blade holder whereby certain important 20 advantages are attained and the device rendered simpler, less expensive and otherwise more convenient and advantageous for use, as will be hereinafter more fully set forth.

25 The novel features of my invention will hereinafter be definitely claimed.

In order that my invention may be the better understood, I will now proceed to describe the same with reference to the accompanying 30 drawing, wherein:

Figure 1 is a view in side elevation of a blade holder constructed in accordance with an embodiment of my invention in assembled relation with a blade applied;

35 Figure 2 is a sectional view taken substantially on the line 2—2 of Figure 1;

Figure 3 is a longitudinal sectional view taken through Figure 1 between the plates of the members with the blade in elevation;

40 Figure 4 is a view in perspective of the blade carrying member unapplied, the applied blade being diagrammatically indicated by broken lines;

Figure 5 is a view in perspective of the 45 body or main member.

As herein disclosed, my improved holder comprises two members A and B one snugly fitting in the other and in a manner to be hereinafter more particularly referred to.

50 As herein disclosed, the member A is stamped from a single sheet of metal of requisite gauge and which comprises two overlying plates 1 integrally connected along similar marginal edges by a substantially cylindrical web 2. The outer longitudinal marginal portions of the plates 1 are

returned, as at 3, to provide a double thickness for reinforcement or strength and also to protect the user against injury as would otherwise be liable to occur by accidental contact with a raw edge of a plate. The plates 1 converge inwardly one toward the other while their outer portions are substantially maintained in a fixed separated relation by the bridging arms 4, each of said arms being preferably integrally formed with one of the plates 1 and bent to overlie the second plate 1 and soldered, welded or otherwise rigidly secured thereto.

The member B also comprises two overlying plates 5 integrally connected along similar marginal portions, the opposite ends of one of the plates 5 being provided with spaced arms 6 integrally formed therewith and bent to overlie the adjacent end portions of the second plate 5 and welded, soldered or otherwise fixedly secured thereto. Between the arms 6 each end of such plate 5 is provided with the outstanding fingers or lugs 7 which, when the member B is forced within the member A between the plates 1 thereof, the contact of these fingers or lugs 7 with the arms 4 limit the extent of insertion of the member B within the member A.

Either of these fingers or lugs 7 may be 85 readily engaged by the digit of a hand to facilitate the removal or separation of the member B with respect to the member A.

The plates 5 of the member B are adapted to have engaged therebetween a portion of a razor blade R of a well known flexible type for use in connection with safety razors. Only a portion of the blade R, however, is received within a member B thus providing an extended or projected part of the blade 95 R which, when the member B is engaged with the member A, is in requisite position to permit the blade to be used for scraping purposes, such as removing paint and other foreign matter adhering to a glass surface or 100 the like. With a blade R operatively comprised within my improved holder, the blade can also be effectively and conveniently employed as a cutter, as for ripping seams, cutting paper, opening cartons and other general cutting operations.

I have also found in practice that my improved holder can be employed to advantage in holding a flexible razor blade for honing and stropping.

When the blade R is not in use, it is to 110 be understood that the member B is to be inserted within the member A with the pro-

jected portion of the blade R inwardly directed, thus assuring effective protection against the action of the blade when the same is not in use. The member B serves to facilitate a requisite engagement of a blade within the member A and the coaction between the members A and B is such to assure a maximum of stress being imposed on the blade R through the member A.

10 While not necessary, it is to be understood that the cylindrical web 2 may be employed as a barrel to permit the member A to be mounted upon the end portion of a suitable handle.

15 From the foregoing description it is thought to be obvious that a blade holder constructed in accordance with my invention is particularly well adapted for use by reason of the convenience and facility with 20 which it may be assembled and operated, and it will also be obvious that my invention is susceptible of some change and modification without departing from the principles and spirit thereof and for this reason 25 I do not wish to be understood as limiting myself to the precise arrangement and formation of the several parts herein shown in carrying out my invention in practice except as hereinafter claimed.

30 I claim:

1. A holder for a razor blade comprising two members, one of said members constituting two overlying plates converging toward their rear margins, the rear marginal 35 portions of said plates being resiliently connected, the forward marginal portions of said plates being spaced apart, arms connecting the outer portions of said plates for positively maintaining such portions of the 40 plates separated, a blade carrying member insertable between the plates of the first member, said blade carrying member having outstanding lugs coacting with the first named member for limiting the extent of insertion of the blade carrying member inwardly of the first named member.

2. A holder for a razor blade comprising two members, one of said members constituting two overlying plates, the rear marginal 45 portions of said plates being resiliently

connected, the forward marginal portions of said plates being spaced apart, arms connecting the outer portions of said plates for positively maintaining such portions of the plates separated, a blade carrying member insertable between the plates of the first member, said blade carrying member having outstanding lugs coacting with the first named member for limiting the extent of insertion of the blade carrying member inwardly of the first named member.

3. A holder for a razor blade comprising two members, one of said members constituting two overlying plates, the rear marginal 60 portions of said plates being resiliently connected, the forward marginal portions of said plates being spaced apart, arms connecting the outer portions of said plates for positively maintaining such portions of the plates separated, a blade carrying member insertable between the plates of the first member, said blade carrying member having outstanding lugs coacting with the first named member for limiting the extent of insertion of the blade carrying member inwardly of the first named member.

4. A holder for a razor blade comprising two members, one of said members constituting two overlying plates converging toward their rear margins, the rear marginal 70 portions of said plates being resiliently connected, the forward marginal portions of said plates being spaced apart, arms connecting the outer portions of said plates for positively maintaining such portions of the plates separated, a blade carrying member insertable between the plates of the first member, said blade carrying member having outstanding lugs coacting with the first named member for limiting the extent of insertion of the blade carrying member inwardly of the first named member.

In testimony whereof I hereunto affix my signature.

CLARENCE E. STRICKLAND.
